UNITED STATES PATENT OFFICE.

TRACY J. ANSTEY, OF OAKLAND, CALIFORNIA.

WEDGE CLOSURE FASTENER.

Application filed April 17, 1926. Serial No. 102,620.

My invention relates broadly to closure fasteners, and it has special reference to wedge door closure fasteners chiefly for holding doors for refrigerators and cold-
5 storage rooms tightly shut by wedge action when the closing of the doors is required.

In refrigerators and cold storage rooms, which are constructed so as to be virtually airtight, the doors therefor that have ordinary latches or fasteners are frequently left ajar, and as a consequence a resultant inrush of air incurs a considerable rise of the temperature in the refrigerators or the cold-storage rooms. When the doors are closing, 10 the air in the refrigerators is compressed and by its reaction the doors remain slightly open until they are actually closed by hand.
15

The principal object of my invention is to provide a fastening device for refrigerator doors and the like which will overcome the before-mentioned objectionable features by positively shutting the door and holding it wedged in the closed position, while at the same time permitting the door to be easily 20 opened at will from either side.

Another object is to provide a closure fastener adapted to be attached to the door of a refrigerator, and to provide a keeper that is adapted to be attached to the door 25 jamb, and to construct the fastener with a spring-actuated, pivotally secured lock plate having a notched portion so arranged that, when the door is nearing its closed position, the notched portion will receive the end of 30 the keeper therein and force the door to its closed position and wedge it in said position, even if the door in the course of time has 35 shrunk away from the jamb.

A further object of the invention is to 40 provide a door closure fastener that has its handle formed as a part of the fastener, and that the fastener will operate by a pull on the handle from the outside or a push on the door from the inside.

Still further objects and advantages will 45 appear with reference to the subjoined specification and the accompanying drawings, in which:

Figure 1 is a front view, showing a portion 50 of a refrigerator door with my closure fastener secured thereto, and a portion of the door jamb with the keeper for the fastener thereon. The fastener is shown as holding the door in its closed and wedged position.

Fig. 2 is a top view of the door and the

jamb, with the fastener and the keeper attached, as shown in Fig. 1. The fastener casing is in mid-section in order to show the working parts therein and particularly how the ball wedges the lock plate against 60 the keeper;

Fig. 3 is a top view analogous to Fig. 2, showing the door partly opened; the casing is partly in section and the lock plate is receding from its engaging position with 65 the keeper; and

Fig. 4 is a top view analogous to Fig. 3, showing the door opened so that the lock plate is out of engagement with the keeper.

Referring to the drawings in detail, the 70 numeral 5 indicates a swinging support, such as a refrigerator door, which is hinged in the ordinary manner to the door frame, not shown. Opposite to the hinge side of the door is secured the fastener member 6 of my 75 invention. This fastener consists of a casing 7, which has outward extending flanges 8 for its securement to the door, as by bolts 9 therethrough. The casing is provided with a longitudinal bore 10, which is 80 threaded at one end and at its other end joins an expanded opening 11 adapted to receive therein a lock plate 12. The lock plate is pivotally secured in the opening by 85 a pin 13 driven through the side walls of the casing.

The lock plate is provided with a notched portion 14, having tongues 15 and 16, and a cam 17 on the other side of the pivot 13 and opposite to the tongue 16. A coil-spring 18 90 is freely mounted in the bore 10, and an element is slidably and rotatably mounted in the bore for engagement with the cam of the lock plate. This element comprises a ball 19, which is seated in the end of the 95 spring toward the lock plate, and the tension at which the ball engages the cam is adjustably governed by means of a screw 20 screwed into the threaded end of the bore.

A stop 21 is formed within the casing at 100 the end of the bore 10 for the tongue 15 in order to stop the swinging movement of the lock plate in one direction. For the purpose of closing and opening the door, the fastener has integral therewith a ring-shaped handle 24, which preferably is in alignment with the bore 10.

The keeper or engaging member of my invention is indicated in general by the numeral 25. It consists of a base 26, which 110

is secured to the jamb or stationary support 23 by suitable means, such as bolts 27. From the base extends a rod 28 which terminates in a head 30 that is adapted to be received within the notched portion 14 of the lock plate for engagement with either of its tongues 15 and 16.

In operation, when the door is closed, as shown in Fig. 2, the ball 19 will be wedged 10 between the cam 17 of the lock plate 12 and the stop 21, so that the door is thus always held tightly when in the closed position. By an outward pull on the handle 24 the head 30 of the keeper 25 causes the lock 15 plate to swing on its pivot 13 and force the ball to compress the spring, as shown in Fig. 3. A moment thereafter, the head, by its sweeping engagement with the tongue 15, will swing the lock plate to a position 20 whereby the spring-actuated ball will wedge as before, and cause the plate to assume the position shown in Fig. 4. The lock plate in this position is clear of the keeper and the door is thus free to be swung further out- 25 ward for access to the refrigerator.

It is seen that, by the outward pull on the door, the tongue 16 is forced to assume a position for operative engagement with the keeper, so that, when the door is swung in- 30 ward and is nearing its closing position, the keeper will engage the tongue 16 and thereby swing the lock plate until it reaches a position in which it will permit the spring-actuated ball to wedge between the cam and 35 the stop, and by the engagement of the tongue 15 with the keeper force the door into the closed position.

From the foregoing description taken in connection with the accompanying drawings, 40 the advantages of the construction and the method of operation will be readily understood by those skilled in the art to which the invention appertains, but while I have described the principle of operation, 45 together with the device which I now consider to be the best embodiment thereof, I desire to have it understood that the device shown is merely illustrative and that such changes may be made, when desired, as fall 50 within the scope of the appended claims.

What I claim as new and desire to secure by Letters Patent of the United States, is:

1. A closure fastener of the character de- 55 scribed comprising a casing adapted to be secured to a swinging support; a lock plate pivotally secured in the casing at one end thereof and provided with a pair of adjacent tongues forming a notched portion and with a cam opposite to one of the tongues; a keeper adapted to be secured to a stationary 60 support and provided with a head adapted to be received within the notched portion for engagement with the tongues; and means within the casing comprising a freely mov- 65 able ball adapted to engage the cam and a

wall of the casing for holding one of the tongues in engagement with the keeper, when the swinging support is nearing its closed position, so as to force the swinging support to the closed position and hold it wedged 70 in said position, and, conversely, when the swinging support has been swung to a position in which the first-named tongue is released from its engagement with the keeper, to move the other tongue to a position for 75 operative engagement by the keeper.

2. A closure fastener of the character de- 80 scribed, comprising a casing adapted to be secured to a swinging support and provided with a longitudinal bore; a lock plate pivotally secured in the casing at one end of the bore and provided with a pair of adjacent tongues forming a notched portion and with a cam opposite to one of the tongues; a keeper adapted to be secured to a stationary support and provided with a head portion adapted to be received within the notched portion for engagement with the tongues; an element slidably mounted in the bore and adapted to engage the cam; and 85 resilient means in the bore adapted to hold the element in engagement with the cam and to co-operate with the element for holding one of the tongues in engagement with the keeper, when the swinging support is nearing its closed position, so as to force the swinging support to the closed position and hold it wedged in said position, and, conversely, when the swinging support has been 90 swung to a position in which the first-named tongue is released from its engagement with the keeper, to move the other tongue to a position for 95 operative engagement by the keeper.

3. A closure fastener of the character de- 100 scribed, comprising a casing adapted to be secured to a swinging support and provided with a longitudinal bore; a lock plate pivotally secured in the casing at one end of the bore and provided with a pair of adjacent tongues forming a notched portion and with a cam opposite to one of the tongues; a keeper adapted to be secured to a stationary support and provided with a head 105 adapted to be received within the notched portion for engagement with the tongues; an element slidably mounted in the bore and adapted to engage the cam; resilient means in the bore adapted to hold the element in engagement with the cam and to co-operate 110 with the element for holding one of the tongues in engagement with the keeper, when the swinging support is nearing its closed position, so as to force the swinging support to the closed position and hold it wedged in said position, and, conversely, when the swinging support has been 115 swung to a position in which the first-named tongue is released from its engagement with the keeper, to move the other tongue to a position for 120 operative engagement by the keeper.

125

sition for operative engagement by the keeper; and means for adjusting the tension of the resilient means.

4. A closure fastener of the character described, comprising a casing adapted to be secured to a swinging support; a lock plate pivotally secured in the casing at one end thereof and provided with a notched portion; a keeper adapted to be secured to a stationary support and provided with a head adapted to be received within the notched portion; means within the casing for holding the notched portion of the lock plate in engagement with the keeper, when the swinging support is nearing its closed position, so as to force the swinging support to the closed position and hold it wedged in said position, and, conversely, when the swinging support has been swung to a position in which the lock plate is released from its engagement with the keeper, to swing the lock plate so that the notched portion is in a position for operative engagement with the keeper; and means comprising a handle integral with the casing for the manipulation of the swinging support.

5. A closure fastener of the character de-

scribed, comprising a casing provided with a longitudinal bore and adapted to be secured to a door; a lock plate pivotally secured in the casing at one end of the bore and provided with a pair of adjacent tongues forming a notched portion and with a cam opposite to one of the tongues; a keeper adapted to be secured to a jamb and provided with a head adapted to be received within the notched portion for engagement with the tongues; a coil-spring freely mounted in the bore; and a ball slidably and rotatably mounted in the bore and seatable in one end of the spring so as to engage the cam to hold one of the tongues in engagement with the keeper, when the door is nearing its closed position, in order to force the door to the closed position and hold it wedged in said position, and, conversely, when the door has been swung to a position in which the first-named tongue is released from its engagement with the keeper, to move the other tongue to a position for operative engagement by the keeper.

In testimony whereof, I affix my signature.

TRACY J. ANSTEY.
